[57] CLAIM

The ornamental design for a scale for weighing precious metals and the like, as shown and described.

DESCRIPTION

FIG. 1 is a front elevational view of a scale for weighing precious metals or the like showing our new design;
FIG. 2 is a rear elevational view thereof;
FIG. 3 is a left side elevational view thereof;
FIG. 4 is a right side elevational view thereof;
FIG. 5 is a top plan view of FIG. 2; and
FIG. 6 is a bottom plan view of FIG. 2.
